EDWIN L. POWELL, OF WASHINGTON, DISTRICT OF COLUMBIA

HIGH-FREQUENCY ELECTRICAL CIRCUITS

Application filed June 7, 1923. Serial No. 643,993.

(GRANTED UNDER THE ACT OF MARCH 3, 1883, AS AMENDED APRIL 30, 1923; 370 O. G. 757)

The principal object of my invention is to provide means for controlling current flow in high frequency electrical circuits, particularly in those circuits employing thermionic vacuum tubes having a feed-back connection between the plate and grid circuits for producing oscillations or for amplifying by what is known as a regenerative action.

A further object is to improve the sharpness of resonance or selectivity of high frequency electrical circuits.

The general practice for controlling the feed-back action between the plate and grid circuits is to provide a variable coupling, either inductive or capacitive, and through the variation of this coupling secure the desired control. This method is undesirable as such circuits are usually tuned for various purposes and when the coupling values are changed merely for the purpose of securing control over the feed-back action the tuning of the circuits is destroyed, requiring additional adjustment to return the circuits to their desired tune.

My invention will be best understood by reference to the accompanying drawing in which I have illustrated it employed in connection with radio reception. A is an antenna having inductance L_1 and variable con-

denser C_1 permitting of tuning the circuit. The antenna is coupled to a secondary tunable circuit containing inductance L_2 and variable capacity C_2 . This circuit is contained in the grid circuit of a three electrode vacuum tube

VT having its filament heated by the battery B_1 , the heating current being controlled by the rheostat R_3 . R_1 is a resistance of the order of megohms and C_3 is a fixed condenser forming what is known as a grid leak-stop- ping condenser combination. The plate circuit of the vacuum tube contains inductance L_3 , telephones T and plate battery B_2 . The condenser C_5 provides a radio frequency by-pass around the high impedance telephones.

The coupling between inductance L_3 of the plate circuit and inductance L_2 of grid circuit forms the required feed-back coupling between these two circuits to produce oscillations or regeneration as desired. The two coils may be wound on the same form F and

thereby given a fixed coupling relation provided this relation is sufficiently large to accomplish the maximum effect required in the particular device, though it may be also desirable to make this coupling variable in order that the device may perform over a wide range of accomplishments. R_2 is a resistance in the filament lead of the grid circuit and C_4 is a variable capacity in shunt with this resistance. It is through this arrangement that I secure the desired control over the high frequency currents in the system. The resistance should be so constructed as to have a minimum of distributed capacity, as it is preferable to vary the effect of this resistance by the use of the variable capacity in shunt therewith, and should the resistance have a large distributed capacity the desired degree of control through a shunted variable capacity will not be obtainable. By varying the capacity C_4 the extent of the by-pass of radio frequency currents around the resistance R_2 is thoroughly under control and by a correct selection of values for these elements with a given amount of feed-back relation between the grid and plate circuits, the operator can cause the system to oscillate, or stop oscillating and regenerate to a greater or lesser degree as desired.

By a correct selection of the value for this resistance, with a given amount of feed-back relation between the grid and plate circuits, the operator can cause the system to oscillate, or stop oscillating and regenerate to a greater or lesser degree as desired.

I have further found that the introduction of such a resistance in a regenerative high frequency circuit greatly improves its sharpness of resonance or selectivity. While I am unable to account for this phenomenon, the improvement is a decided one; so much so, that I have found a single circuit radio receiver of the regenerative type containing my invention equally as selective as a two or coupled circuit regenerative receiver not containing my invention.

As an example of the values which may be employed in connection with my invention, in a regenerative receiving circuit designed to operate between 200 and 600 meters wave

length, I employed a very low distributed capacity resistance element of 2000 ohms having in shunt therewith a condenser variable from practically zero to .0005 microfarads.

5 While I have illustrated and described my invention in connection with its use in a regenerative radio receiving circuit, other applications are readily apparent to those skilled in the art, and I do not desire to be limited to this merely illustrative use.

10 While I have illustrated and described the oscillation controlling resistance as being effectively varied by a shunted condenser, it is readily apparent that equally effective control may be had by providing a resistance adjustable in magnitude without necessitating other variable means connected in shunt thereto. It has been found however, that the shunted capacity method provides a particularly smooth means of control.

15 The invention herein described may be manufactured and used by or for the Government of the United States for governmental purposes without the payment to me of any royalty thereon or therefor.

20 Having described my invention I claim:—

25 In a regenerative vacuum tube detector circuit having a grid-filament and plate-filament circuits inductively coupled together, the combination in the grid-filament circuit of a coil, a variable condenser in parallel therewith, a grid-condenser and its parallel leak resistor of high ohmic resistance connected between one terminal of said condenser and the grid of said tube, means for controlling the degree of reaction between the grid-filament and plate-filament circuits comprising a second resistor of relatively low ohmic resistance connected between the other terminal of said condenser and the filament of said tube and a second variable condenser in parallel with said last mentioned resistance.

EDWIN L. POWELL.
